UNITED STATES PATENT OFFICE.

FRANK M. ASHLEY, OF NEW YORK, N. Y.

DESIGN FOR AN INKSTAND.

42,077.

Specification for Design.

Patented Jan. 9, 1912.

Application filed September 28, 1909. Serial No. 520,601. Term of patent 7 years.

To all whom it may concern:

Be it known that I, FRANK M. ASHLEY, a citizen of the United States, residing at New York city, in the county of Kings and State of New York, have invented a new, original, and ornamental Design for an Inkstand, for which the following is a specification, reference being had to the accompanying drawings, forming a part thereof, and in which the figure is a perspective view of an inkstand bearing and incorporating my design.

A indicates the body portion of the inkstand containing the reservoir for the ink. This body portion is of rectangular form and having a greater length than width, and a considerably less height than width. A thin cover B is provided, which is of less length than body portion A, and is disposed adjacent one edge of the body so as to expose

a portion of the top of the body portion when the cover is in a position to close the reservoir. Raised curved portions B' may be provided on the cover, forming recesses C—C to serve as a pen rack.

The essence of my invention resides in the general form and relative proportions of the base and cover, which present to the eye an appearance of a low, comparatively wide construction, having a very neat and artistic effect.

I claim—

The ornamental design for an inkstand as shown and described:

FRANK M. ASHLEY.

Witnesses:

HARRY W. WILKES,
MINNIE S. MILLER.
